UNITED STATES PATENT OFFICE

RAY R. SMITH, OF CLARKSBURG, WEST VIRGINIA

FLUSH LEVER AND BULB

Application filed August 30, 1930. Serial No. 479,015.

This invention relates to improvements in flush tanks for toilets, the general object of the invention being to provide means for insuring seating of the valve after the flushing action by providing a spring for moving the valve lever to its normal position after the same has been raised by its handle and to provide guide means for the valve for guiding it upon its seat.

10 This invention also consists in certain other features of construction and in the combination and arrangement of the several parts, to be hereinafter fully described, illustrated in the accompanying drawings and specifically 15 pointed out in the appended claims.

In describing the invention in detail, reference will be had to the accompanying drawings wherein like characters denote like or corresponding parts throughout the several views, and in which:—

Figure 1 is a sectional view through a tank, showing the valve and its operating means.

Figure 2 is a top plan view of Figure 1.

Figure 3 is a sectional view through the 25 valve.

Figure 4 is a sectional view through the seat of the valve, with the valve in elevation.

Figure 5 is a perspective view of the guide for the lower end of the valve stem.

30 In these drawings, the letter A indicates a part of the flush tank and the letter B a part of the outlet from the tank, the upper part of which forms a valve seat 1 for the bulb valve 2. A tube 3 passes through the

35 valve and has its ends threaded, the upper end receiving the rod or stem 4 which passes through the guide 5 attached to the overflow tube 6 and a short rod 7 is threaded into the lower end of the tube. A channel shaped

40 plate 8 extends across the opening 9 in the valve seat and has a hole 10 therein through which the rod 7 passes so that said plate and rod act as guiding means for the valve and insure the proper seating of the valve. A

45 perforated ear 11 extends outwardly from one end of the plate 8 for receiving a screw 12 which fastens the plate to a part of the valve seat.

A short arm 13 is fastened at one end to the bushing 14 through which the shaft 15

extends to which the operating handle 16 is connected. The other end of the arm 13 has an upwardly extending part 17 and a substantially bell crank lever 18 is pivoted at the junction of the part 17 with the major part of the arm 13. A link 19 connects the short arm of the bell crank 18 with the arm 20 connected with the inner end of the shaft and the long arm of the bell crank is connected by the link 21 with the upper end of the rod 4, this latter connection being a sliding one, as usual. A spring 22 has one end connected with a pin 23 at the upper end of the part 17 of the arm 13 and the spring passes around the pivotal point 24 of the bell crank and has its opposite end hooked over the long arm of the bell crank.

From the foregoing it will be seen that when it is desired to flush the tank, the handle 16 is turned in the usual manner so that the arm 20 will exert a pull upon the link 19 and thus cause the link to swing the bell crank upwardly against the action of the spring 22 so that the link 21 will lift the valve 2 off its seat. When the handle is released, the 70 spring 22 will swing the bell crank downwardly so that the valve can seat as soon as the water leaves the tank and the rod 7 and the guide 8 insure the valve engaging its seat. Thus this invention will insure accurate seating of the flush bulb and prevents water from leaking through the tank through improper seating of the bulb.

It is thought from the foregoing description that the advantages and novel features 80 of the invention will be readily apparent.

It is to be understood that changes may be made in the construction and in the combination and arrangement of the several parts, provided that such changes fall within the 85 scope of the appended claims.

What I claim is:—

1. In combination with a flush tank valve, guiding means at the lower end of the valve for guiding the same upon its seat, a manually operated spring pressed sectional lever one section being swingingly supported and the other section pivoted to the latter and adapted for raising the valve, the spring acting to tension the sections of the lever and a 100

hand piece having connection with the section engaged with the valve for moving both sections successively.

2. In combination with a flush tank and its valve, a bell crank lever pivoted to the wall of the tank, a lever connected with the valve and pivoted to the first mentioned lever, whereby the valve is moved when the levers are swung, means for swinging the last named lever and a spring at the pivotal connection between the lever, and having ends connected respectively with the lever.

15 In testimony whereof I affix my signature.
RAY R. SMITH.
